UNITED STATES PATENT OFFICE.

PHILIP M. GUNDLACH AND JOHN P. GUNDLACH, OF BELLEVILLE, ILLINOIS.

WHEEL-HUB.

SPECIFICATION forming part of Letters Patent No. 693,267, dated February 11, 1902.

Application filed August 27, 1900. Serial No. 28,181. (No model.)

To all whom it may concern:

Be it known that we, PHILIP M. GUNDLACH and JOHN P. GUNDLACH, of Belleville, in the county of St. Clair and State of Illinois, have 5 invented certain new and useful Improvements in Wheel-Hubs; and we do hereby declare the following to be a full, clear, and exact description of the same, reference being had to the accompanying drawings, forming 10 a part of this specification.

The present invention relates to sectional metallic hubs for vehicle-wheels in which the spokes alternate and are dished in opposite directions.

15 The object of the present improvement is to provide a simple and efficient sectional hub construction which affords means for firmly drawing the inner and adjacent edges of the oppositely-arranged series of spokes together 20 to effect a firm and rigid bracing of the outer ends of such spokes against the felly or rim of the wheel and which also affords a simple and convenient means for introducing an extension washer or disk beneath any one of the 25 spokes after the same has become loosened by shrinkage, all as will hereinafter more fully appear and be more particularly pointed out in the claims. We attain such object by the construction and arrangement of parts 30 illustrated in the accompanying drawings, in which—

Figure 1 is a detail front elevation of a wheel-hub embodying the present invention with portions of the spokes shown in position; 35 Fig. 2, a plan view of the hub; Fig. 3, a detail longitudinal section at line $\alpha\alpha$, Figs. 1 and 2; Figs. 4 and 5, detail plan views illustrating modified forms of the fastening means for the hub-sections.

40 Similar numerals of reference indicate like parts in the several views.

Referring to the drawings, 1 and 2 represent the main outer and inner hub-sections of the present invention, of a substantially 45 similar construction and arranged in axial alinement, as shown in Figs. 2 and 3 of the drawings, their alinement being attained by the socket-sleeve 3, which in addition covers and protects the seam or joint at the point of 50 contact between the two sections. Each of the main sections aforesaid will comprise a

cylindrical body portion, from the periphery of which project the radial series of half or semi circular sockets 4 5, the open sides of which face outward, as shown, to permit of 55 the ready introduction of the spokes in an assemblage of the wheel or in a repair of the same, and said open-sided sockets are provided with inwardly-extending bracing-ribs 6 to strengthen the same, and, in connection 60 with notches 7 in the socket-sleeve 3, insure the proper position of the two main sections with relation to each other and which proper relation of the main sections involves a staggered or alternate relation of the spoke-sock- 65 ets 4 and 5, as shown in Fig. 2.

The series of half or semicircular sockets 4 and 5 are provided with removable closure-pieces 8 9 of a semicircular form, which in our preferred construction, as shown in Figs. 70 1 and 2, are connected together in pairs by a connecting-web 10, so as to afford a convenient bearing for the ends of the obliquely-extending clamping-bolts 11, by which the two main sections 1 and 2 are rigidly and substan- 75 tially drawn and held together in the preferred form of our present invention.

In the modified form of the present invention (illustrated in Fig. 4) the removable semi-circular closure-piece for the main sockets of 80 the hub-sections are shown as individual to each main socket, and strap-bolt 12 is shown as the equivalent of the oblique bolt 11 of our preferred construction.

In the modified form shown in Fig. 5 the 85 removable semicircular closure-pieces are shown provided with hook-shaped lugs 13, adapted to engage ribs 14 at the sides of the main sockets to effect an engagement of the parts and dispense with the use of the clamp- 90 ing-bolts 11 and 12.

With the present improvement as any particular spoke becomes loosened through shrinkage, &c., the particular cap or closure-piece 8 or 9 confining same can be removed, 95 and by means of the usual spoke-jack the parts can be forced apart, so that a reinforce-washer 15 (see Fig. 3) can be introduced beneath the spoke end to compensate for such shrinkage, after which the cap or closure 100 piece can be replaced.

Having thus fully described our said inven-

tion, what we claim as new, and desire to secure by Letters Patent, is—

1. In a wheel-hub, the combination of a pair of hub-sections formed with half-sockets, the 5 open sides of which face outward, the one series of which are staggered with relation to the other, removable caps or closure-pieces for such sockets united together in pairs by a connecting - web, and obliquely-arranged bolts 10 for securing the cap or closure-pieces in place and for drawing the two main hub-sections together, substantially as set forth.

2. In a wheel-hub, the combination of a pair of hub-sections formed with half-sockets, the 15 open sides of which face outwardly to permit of the insertion of a reinforce-washer beneath the spoke end when required, a removable cap or closure-piece for said sockets, a socket-sleeve receiving the adjacent ends of the respective hub-sections, and means for drawing the two main hub-sections together, substantially as set forth.

3. In a wheel-hub, the combination of a pair of hub-sections formed with half-sockets, the 25 open sides of which face outward, the one series of which are staggered with relation to the other, a removable cap or closure-piece for said sockets a socket-sleeve receiving the adjacent ends of the respective hub - sections, and 30 means for drawing the two main hub-sections together the same comprising a series of

obliquely-arranged bolts, substantially as set forth.

4. In a wheel-hub, the combination of a pair of hub-sections formed with open-sided sockets that face outwardly, inwardly-extending bracing-ribs for said sockets, a removable open - sided closure- cap for such sockets, a socket-sleeve provided with notches in its opposite edges and adapted to receive the adjacent ends of the respective hub-sections, and means for drawing the two main hub-sections together, substantially as set forth. 35 40

5. In a wheel-hub, the combination of a pair of hub-sections formed with open-sided sockets that face outwardly, inwardly-extending bracing-ribs for said sockets, a removable open-sided closure-cap for such sockets, a socket-sleeve provided with notches in its opposite edges and adapted to receive the adjacent ends of the respective hub-sections, and means for drawing the two main hub-sections together, the same comprising a series of obliquely-arranged bolts, substantially as set forth. 45 50

In testimony whereof witness our hands this 24th day of August, 1900.

PHILIP M. GUNDLACH.
JOHN P. GUNDLACH.

In presence of—

D. F. MILLER,
DAN CARDIE.
